UNITED STATES PATENT OFFICE.

PAUL Z. FUNK, OF JEROMEVILLE, OHIO.

MOLD.

1,294,254.

Specification of Letters Patent. Patented Feb. 11, 1919.

Application filed May 15, 1918. Serial No. 234,746.

To all whom it may concern:

Be it known that I, PAUL Z. FUNK, a citizen of the United States, residing at Jeromeville, in the county of Ashland and 5 State of Ohio, have invented certain new and useful Improvements in Molds, of which the following is a specification.

This invention relates to molds, and more particularly to a mold especially adapted 10 for casting articles of concrete and other plastic material.

One of the main objects of the invention is to provide a form of the character stated 15 of simple construction and operation so constructed as to permit a number of units to be assembled in a group or battery for casting a number of articles simultaneously. A further object is to provide a mold comprising a collapsible core, and an outer casing 20 which supports this core and is formed of a plurality of members so connected as to be readily disassembled or set up. Another object is to provide a mold the various 25 parts of which may be readily formed by stamping and bending from sheet metal of suitable gage, thus insuring low cost of production. Further objects will appear from the detailed description.

In the drawings:

30 Figure 1 is a side view of a mold constructed in accordance with my invention, as used,

Fig. 2 is a top plan view partly in section, Fig. 3 is a transverse vertical section,

35 Fig. 4 is a fragmentary longitudinal section,

Fig. 5 is an end view of a concrete block formed in the mold,

Fig. 6 is a detail of the means for expanding and collapsing the mold core.

The outer casing or body of the mold is 40 of substantially rectangular cross section and is formed of side plates 1, bottom plates 2, and end plates 3. Each of the side plates 45 1 is turned over at its inner end to provide an outer annular flange 4 having a depending inwardly directed arm 5, the members 4 and 5 forming a downwardly tapering bead. The lower end of member 5 is 50 so spaced from the outer face of plate 1 as to provide a slot or opening which snugly receives a vertical flange 6 formed at the end of end plate 3. Each end plate is provided, at each end, with a head which forms outwardly directed flanges projecting to each

side of the end plates, these flanges acting to suspend the side plates 1 in the manner illustrated. These side plates are provided, at their lower edges, with integral inwardly directed horizontal flanges 7 which fit beneath and support the bottom plate 2. By this arrangement the side plates and the bottom plate are suspended from the end plates, and all of these members are so connected as to be readily disassembled, or assembled, as desired.

In connection with the outer casing or body described, I employ a core indicated generally by 8. This core is of substantially rectangular cross section and is composed of a plurality of, in this case 6, plates which are hingedly secured together. The top and bottom of the core are each formed of a single plate 9 and 10, respectively, the sides being formed from two plates 11 and 12 which are hingedly secured together at the center of each side and are hingedly secured to the edges of the top and bottom plates. An arm 13 is pivotally secured at its outer end on the inner face of each plate 11 adjacent the lower edge thereof. These arms project inwardly of the mold and have their overlapping inner ends pivotally secured together as at 14. Each arm 13 has a portion of its base which is mounted on the 50 plate turned at right angles to provide an operating crank 15. By turning this crank, the arm 13 may be moved into or out of horizontal position. When the arms 13 are moved into horizontal position they are 55 brought into alinement so as to extend the toggle which is produced by these arms. This results in extending or straightening the sides of the core so as to hold it rigidly in position as illustrated in Fig. 3. In practice, the core in its collapsed condition will be placed in the mold, being inserted through suitable openings provided in the end plates 3 for this purpose. After the mold has 60 been placed in proper position, the arms 13 are moved into horizontal position so as to expand the mold and hold it rigidly in shape, as illustrated. The cement mixture from which a block is to be formed is then poured into the mold about the core 8 and, after this mixture has started to set, the mold is then removed, the block formed being placed in a suitable shed to be cured. In removing the mold, the core is first 65 collapsed by turning the arms 13 upward into 70

substantially the position indicated in Fig. 3, thus forcing the sides of the mold toward each other and lowering the top and bottom plates. When thus collapsed, the core may 5 be readily removed, after which the end, bottom and side plates may be removed.

As will be noted, each side plate 1 is provided with a suitable groove or depression 1^a and the end plate is provided with 10 a substantially rectangular member 16 which forms projections extending beyond each face of this plate, this member corresponding in width to the distance between the inner face of element 1^a of side plate 1 and the 15 side face of the core 8. In practice, these projections form openings or hand holds through the sides of the block which is molded, as indicated by 17 in Fig. 5. The members 1^a of the side plates 1 provide 20 depressions or channels in the sides of the block which reduce the weight thereof without weakening the block formed. In laying these blocks, the faces in which these depressions or channels are formed will form the 25 upper and lower faces of the block, so that the channels of one layer of blocks will register with the channels of a superposed layer thus forming continuous air passages between the blocks. The hand hold 17 30 communicates with the main air passage formed by the core in the center of the block, and this insures circulation of air about and through all of the tiers of blocks. These hand holds also provide convenient means 35 for handling the block and for permitting them to be drawn into proper relation when they are being laid.

In practice, the core 8 may be made of any 40 desired or suitable length and inserted through a number of plates corresponding to the end plates 3 which are positioned at equal distances apart and support the side and bottom plates 1 and 2 in the manner 45 previously described. This will be clear from Figs. 1, 2 and 4 of the drawings. In Figs. 1 and 2, I have shown two sections 50 formed from the end plates and side plates secured together in the manner previously described, all of these plates being provided 55 with suitable openings which are adapted to receive the core 8. By providing a core of suitable length, it is possible to form a mold which is divided into a number of sections or parts longitudinally, each part representing a space for forming or casting a 60 block. This renders it possible to cast a comparatively great number of blocks simultaneously and by the use of but one mold so that, when these blocks have set for a 65 short time, the molds may be readily disassembled and again set up and a second batch of blocks cast. By providing a suitable number of these molds, the blocks may be formed continuously in batches thus rendering 70 it possible to produce a great number

of blocks in a relatively short time. In forming end blocks which it is desired to have closed at one end, I substitute a continuous plane plate 3^a for the usual end plate. This plate 3^a is of continuous cross 70 section, and the mold 8 instead of being inserted through plate 3^a has its inner end closed by a closure cap 8^a which fits tightly 75 therein, the end of this mold being spaced a suitable distance from the inner face of plate 3^a. The material is then poured about the mold between plate 3^a and plate 8^a, and the block thus produced will be similar to the outer blocks with the exception that it will be closed at one end by the materials 80 which flows between the closure member or cap 8^a of the mold and the central portion of plate 3^a. This renders it possible to produce block closed at one end and thus adapted 85 for use as end blocks and for similar purposes. It will be understood, of course, that the length of the side plates and bottom plate 2 may be varied, thus rendering it possible 90 to produce blocks of different lengths for particular purposes.

In the molds thus produced, the core as well as the body portion of the mold may be formed from sheet metal and therefore made at very small cost. In addition, the side, end and bottom plates of the body of 95 the mold are so connected and related as to do away with all necessity of supplemental securing means, thus producing a mold which may be readily assembled or disassembled and which requires no special tools 100 for this purpose.

The foregoing description and the drawings have reference to what may be considered the preferred, or approved form of invention. It is to be understood that I may 105 make such changes in construction and arrangement and combination of parts, materials, dimensions, etc., as may prove expedient and fall within the scope of the 110 appended claims.

Having thus fully described my invention, what I claim as new and desire to secure by Letters Patent is:

1. In a mold of the character described, a 115 casing comprising end plates provided at each end with vertically extending flanges, side plates provided at their upper edges with outwardly directed beads engaging over the flanges of the end plates so as to detachably suspend the side plates from the 120 end plates, said side plates being further provided adjacent their lower edges with inwardly directed supporting flanges, and a bottom plate supported by said flanges.

2. In a mold of the character described, a 125 casing comprising end plates having openings therein and provided at each end with vertically extending flanges, side plates provided at their upper edges with outwardly directed beads engaging over the 130

flanges of the end plates so as to detachably suspend the side plates from the end plates, said side plates being further provided adjacent their lower edges with inwardly directed supporting flanges, a bottom plate supported by said flanges, and a collapsible core positioned within said casing and extending through the openings in the end plates so that the end plates form a support therefor.

3. In a mold of the character described, a sectional casing and a core supported therein, said core comprising top and bottom plates, side plates hingedly connected to the

top and bottom plates, said side plates being formed in two sections hinged at their meeting edges, a rod pivotally connected to one section of each side plate and the free ends of said rod being pivotally connected together, and a crank formed on one of said rods for operating the rod to collapse the core.

In testimony whereof I affix my signature in presence of two witnesses.

PAUL Z. FUNK.
